FIG. 11.

FIG. 12.

FIG. 1 is a side elevation of a mixer for liquids or the like embodying my new design;

FIG. 2 is a front elevation thereof;

FIG. 3 is a rear elevation thereof;

FIG. 4 is a top plan view thereof;

FIG. 5 is a side elevation of a modified form of the design, as shown in FIG. 1;

FIG. 6 is a front elevation thereof, as shown in FIG. 5;

FIG. 7 is a rear elevation thereof, as shown in FIG. 5;

FIG. 8 is a top plan view thereof, as shown in FIG. 5;

FIG. 9 is a side elevation of a modified form of the design, as shown in FIG. 1;

FIG. 10 is a front elevation thereof, as shown in FIG. 9;

FIG. 11 is a rear elevation thereof, as shown in FIG. 9;

FIG. 12 is a top plan view thereof, as shown in FIG. 9.

The coupling guard and the electric motor shown in broken lines are for illustrative purposes only.

I claim:

The ornamental design for a mixer for liquids or the like, substantially as shown and described.
